UNITED STATES PATENT OFFICE

158,671

AUTOMOBILE HOOD Porthole PLUG

Joseph M. Kline, Indianapolis, Ind.

Application April 6, 1949, Serial No. 1,832

Term of patent 3½ years

(Cl. D14—6)

To all whom it may concern:

Be it known that I, Joseph M. Kline, a citizen of the United States of America, residing at Indianapolis, Marion County, Indiana, have invented a new, original, and ornamental Design for an Automobile Hood Porthole Plug, of which the following is a specification, reference being had to the accompanying drawing, forming a part thereof.

In the drawing:

Fig. 1 is a top plan view of an automobile hood porthole plug embodying my new design;
Fig. 2 is a front elevational view thereof;
Fig. 3 is a side elevational view thereof;
Fig. 4 is a rear elevational view thereof;
Fig. 5 is a sectional view on the line 5—5 in Fig. 1; and

Fig. 6 is an inside plan view thereof.

I claim:

The ornamental design for an automobile hood porthole plug, substantially as shown.

JOSEPH M. KLINE.
